UNITED STATES PATENT OFFICE.

WILLIAM ERNEST BOUTON, OF SCHENECTADY, NEW YORK.

REINFORCED AWNING SEAM.

Application filed January 24, 1921. Serial No. 439,529.

To all whom it may concern:

Be it known that I, WILLIAM E. BOUTON, a citizen of the United States, residing at Schenectady, in the county of Schenectady 5 and State of New York, have invented new and useful Improvements in Reenforced Awning Seams, of which the following is a specification.

The present invention relates to improvements in reenforced awning seams and has for an object to provide, in conjunction with the overlapped and interlocked edges of awning cloth sections, a reinforcing tape of a substantial width extending beneath the interlocked and overlapped edges and to appreciable distances at both sides of such edges, the tape being secured not only to the cloth or canvas sections of the awning by rows of stitching near its longitudinal edges, 15 but further by rows of stitching at the intermediate portion of the tape which secure it to the overlapped and interlocked edges at the seam.

Although the invention is entitled and 25 referred to as a reenforced awning seam, it is to be understood that the invention is not restricted to this particular use but extends to all cloth constructions, and more particularly to seaming in tents and heavy wear- 30 ing apparel generally.

With the foregoing and other objects in view, the invention will be more fully described hereinafter, and will be more particularly pointed out in the claim appended 35 hereto.

In the drawings, wherein like symbols refer to like or corresponding parts throughout the several views,

Fig. 1 is a fragmentary top plan view of a 40 reenforced seam constructed according to the present invention;

Fig. 2 is a bottom plan view of the same; and

Fig. 3 is a transverse sectional view taken 45 on the line 3—3 in Fig. 1.

Referring more particularly to the drawings, 4 and 5 designate two pieces or sections of awning cloth or canvas or tent or wearing apparel material; and in accordance with the usual practice in awning construction, the adjoining edges at the seam are overlapped and interlocked, as more particularly illustrated in Fig. 3.

At 6 is represented the overturned edge of 50 the section 4, while 7 represents the edge of the section 5 which is returned upon itself

and interlocked with the overturned edge 6. This construction provides four thicknesses at the seam, and moreover yields an interlock between the edges which is found 60 in practice to form a strong construction necessary to withstand strains and stresses to which awnings, tents and the like are subjected in usage.

According to the invention I employ a 65 long piece of tape of substantial width having an offset intermediate portion 8 fitting about the seam formed by the overlapped and interlocked edges 6 and 7 and which contributes an additional thickness to the 70 seam reinforcing it. The sides 9 and 10 of the tape extend at considerable distances to the sides of the seam and lie flat against the adjacent faces of the cloth sections 4 and 5. Lines of stitching 11 and 12 pass 75 through the sides 9 and 10 of the tape and through the cloth sections 4 and 5 by which these parts are secured together. These lines of stitching are made close to the longitudinal edges of the tape and at considerable 80 distances from the intermediate offset portion 8.

Further rows of stitching 13 and 14 are made to pass through the intermediate offset portion 8 of the tape and through the various overlapped and interlocked edges 6 and 7 of the cloth sections so as to bind these parts in their interlocked and overlapped relation and at the same time to secure the intermediate portion of the tape thereto by 85 means of substantially parallel lines of stitching that are situated comparatively close together and which therefore form an exceedingly strong structure.

The seam, it will be noted, is very compact at the overlapped and interlocked edges of the cloth and at the intermediate offset portion of the tape 8, the stitching 13 and 14 being placed close together so that when 90 stresses occur either longitudinally or transversely in the cloth or canvas they do not to any material extent stretch the portions of the cloth and tape directly at the seam.

The side portions 9 and 10 of the tape which are stitched to the cloth will yield to a 105 certain extent in order to absorb these stresses in the comparatively great areas existing between the side rows of stitching 11 and 12 and the intermediate rows 13 and 14 and consequently strains which tend to rip 110 the stitching will be diminished greatly in effect through this distance. Moreover the

bent portions of the sides of the tape will tend to straighten out under strains and this will further relieve the seam of any destructive effect.

5 The taped seam as I have constructed it is very useful for heavy constructions such as awnings, tents, wearing apparel and the like, but it may be used with advantage in various other fabric structures.

10 It is obvious that various changes and modifications may be made in the details of construction and design of the above specifically described embodiment of this invention without departing from the spirit there-
15 of, such changes and modifications being restricted only by the scope of the following claim.

What is claimed is:—

An awning construction comprising adja-
20 cent pieces of canvas having their meeting edges overlapped and folded toward one an-

other, the folded edges being inter-locked forming four plies of material at the joint, the outer plies of material being off-set above and below the plane occupied by the canvas 25 pieces, a reinforcing tape lying beneath the awning and having an intermediate downwardly off-set portion adapted to fit closely in contact with the lowermost ply of the joint and having its edges extending in contact with the under portions of the two canvas pieces, two spaced apart intermediate lines of stitching passing through the four plies of the joint and opposite longitudinal edges thereof, said stitching made to also 30 pass through lateral parts of the downwardly off-set intermediate portion of the tape, and other lines of stitching passing through the raised lateral portions of the tape and the respective pieces of canvas. 35

WILLIAM ERNEST BOUTON.
